COMBINED HIGH INTENSITY LIGHT AND RADIO

Stephen Heller, Spring Valley, N.Y., assignor to
Ovitron Corporation

Filed Oct. 12, 1966, Ser. No. 4,254

Term of patent 14 years

(Cl. D48—20)

FIG. 1

FIG. 2

FIG. 3

FIG. 4

FIG. 1 shows in front perspective a view of my design for a combined high intensity light and radio;

FIG. 2 shows said combination in front elevation;

FIG. 3 shows said combination in side view;

FIG. 4 shows said combination from the rear.

I claim:

The ornamental design for a combined high intensity light and radio, substantially as shown.
